Primary Examiner — Sheryl Lane*Assistant Examiner* — Mark T. Philipps(74) *Attorney, Agent, or Firm* — Leres Patent & Technology, LLC; Mandy L. Tran(57) **CLAIM**

I claim the ornamental design for a vehicle oil pan drain key, substantially as shown and described.

DESCRIPTION

FIG. 1 is a top perspective view of the invention.

FIG. 2 is a bottom plan view of the invention.

FIG. 3 is a top plan view of the invention.

FIG. 4 is a right side perspective view of the invention.

FIG. 5 is a front side perspective view of the invention.

FIG. 6 is a left side perspective view of the invention; and,

FIG. 7 is a rear side perspective view of the invention.

The broken lines represent portions of the article and form no part of the claimed design.

1 Claim, 4 Drawing Sheets---
